UNITED STATES PATENT OFFICE.

BURT EDWARD LLOYD, OF NEW YORK, N. Y.

COMBINED FLYING AND SPINNING TOP.

1,167,507.

Specification of Letters Patent.

Patented Jan. 11, 1916.

Application filed April 24, 1915. Serial No. 23,625.

To all whom it may concern:

Be it known that I, BURT E. LLOYD, a subject of the King of Great Britain, and a resident of the city of New York, borough 5 of Manhattan, in the county and State of New York, have invented a new and Improved Combined Flying and Spinning Top, of which the following is a full, clear, and exact description.

10 This invention relates to toys, and more particularly to flying and spinning tops of that type in which the flying element is given a high rotative speed by being moved quickly along a screw and finally thrown off 15 the same, whereby the said element will fly through the air and ultimately light on the ground, floor or other surface and spin until its force is expended.

The invention has for its general objects 20 to improve the construction of devices of the character referred to so that the toy will be reliable and satisfactory in use, comparatively inexpensive to manufacture, and so designed that the pitch of the blades can be 25 altered, causing the spinning element to be sustained a suitable length of time in the air, or to descend immediately and operate as a spinning top.

A further object of the invention is the 30 provision of a toy including a spinning element provided with bendable vanes or wings and including a conical hub which serves as a spinning point, and if desired the hub can be a double cone, whereby the top can spin 35 against a ceiling or on the floor.

With such objects in view, and others which will appear as the description proceeds, the invention comprises various novel features of construction and arrangement of 40 parts which will be set forth with particularity in the following description and claims appended hereto.

In the accompanying drawing which illustrates one embodiment of the invention, and 45 wherein similar characters of reference indicate corresponding parts in all the views, Figure 1 is a perspective view of the toy with a portion of the runner in section; Fig. 2 is a plan view of the spinning element; Fig. 3 is a sectional view on the line 3—3, Fig. 2; Fig. 4 is a similar view showing the wings or blades in a different position from that shown in Fig. 3; and Fig. 5 is a sectional view of the spinning element with a 55 double cone hub.

Referring to the drawing, 1 designates a screw which is in the form of a flat rod twisted so that its edges form helices, one end of the rod being shaped into a grip 2 of ring or any other suitable form. Freely 60 slidable on the screw 1 is a runner 3 of spool or any other shape, the same having a bore 4 of large enough diameter that the runner can be moved quickly longitudinally of the screw without impedance. The spinning 65 element A comprises a circumferential ring 5 connected with radial wings or blades 6 which have their inner ends connected with a hub 7 of hollow conical form, the vertex 8' of which has a rectangular or non-circular 70 opening 8 to conform to the cross-sectional shape of the rod from which the screw 1 is made, so that by movement of the spinning element A longitudinally of the rod, the 75 said element will acquire a rapid rotation. The point of the cone engages in the upper end of the bore of the runner so that there is only a line contact between the runner and the spinning element, whereby friction is minimized. The blades are flexibly connected at their ends with the ring 5 and hub 7, so that the blades can be pitched at any 80 desired angle. As shown in Figs. 1 and 3, the blades are set so that when the spinning element is thrown off the upper end of the 85 screw the spinning element will ascend, the height of ascent depending upon the rotative speed, and the direction of flight will be determined by inclining the screw out of the vertical. The spinning element will not 90 lose its rotative movement until it descends and spins for some time along the floor or other surface. If the ascending flight is not desired the blades or wings 6 can be bent so as to lie in the plane of the ring 5, as 95 shown in Fig. 4, and therefore the force of gravity predominates and causes the spinning element to quickly descend after being thrown off the upper end of the screw, and consequently the top will spin a long time 100 on the floor. If desired, the vanes or wings can be bent downwardly, as indicated by the dotted lines in Fig. 4.

In the modification shown in Fig. 5 the hub 7 is made of two oppositely disposed 105 cones 9 and 10 having non-circular openings 11 at the points for the operating screw 1. With this form it is possible to cause the top to spin against a ceiling. It will be noted that in all forms of the invention the cone 110

or cones will be of such altitude that the point or points will lie beyond the tips of the blades or vanes, so that the latter will not interfere with the spinning element spinning on the floor or ceiling.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A toy of the class described comprising a screw, a runner having a bore through which the screw passes, the end surface of the runner and the bore thereof forming a circular edge, and a spinning element having a conical hub provided with an opening engaging the screw for receiving rotation therefrom by movement of the element longitudinally of the screw, said hub having its external surface bearing and rotatable on the said circular edge.

2. A toy of the class described comprising a screw, a runner movable freely along the same, a spinning element having a conical hub forming a spinning point, and said point having an aperture fitting the screw, whereby the spinning element receives rota-

tion by movement longitudinally of the screw.

3. A toy of the class described comprising a screw, a runner movable freely along the same, a spinning element having a conical hub forming a spinning point, and said point having an aperture fitting the screw, whereby the spinning element receives rotation by movement longitudinally of the screw, said spinning element embodying vanes adjustable to any desired pitch.

4. A combined flying and spinning top comprising a screw, a runner movable along the same, a spinning element including vanes disposed in a plane transverse to the screw, and a hub to which the vanes are connected, said hub being in the form of a cone depending below the plane of the vanes and having a point on which the element spins on a surface, and the point having an aperture shaped to correspond to the cross-sectional shape of the screw.

5. A combined flying and spinning top comprising a screw, a spinning element provided with vanes and having an oppositely pointed hub through which the screw extends for imparting rotation to the spinning element by longitudinal movement of the latter along the screw, one point serving to permit the said element to spin against a ceiling or on a floor.

In testimony whereof I have signed my name to this specification in the presence of two subscribing witnesses.

BURT EDWARD LLOYD.
